UNITED STATES PATENT OFFICE.

AMBROSE RIDD, OF NEWPORT, KENTUCKY.

ANNEALING-FURNACE.

No. 800,618.

Specification of Letters Patent.

Patented Sept. 19, 1905.

Application filed November 2, 1904. Serial No. 231,145.

To all whom it may concern:

Be it known that I, AMBROSE RIDD, a citizen of the United States, residing at Newport, in the county of Campbell and State of Kentucky, have invented a new and useful Annealing-Furnace, of which the following is a specification.

This invention relates to apparatus employed for the manufacture of sheet metal, and more especially what are known as "black sheets" used in the manufacture of tin and terne plates.

The principal object of the invention is to provide a portable annealing-furnace that may be placed close to the rolls in order to receive the sheets of metal before there is time for any cooling or chilling, said sheets being retained within the furnace until the annealing operation is completed, or the furnace serving as a reheater or temporary receptacle for the sheets, from which they may be again drawn for rerolling.

A further object of the invention is to provide a novel form of portable furnace in which the necessary temperature may be attained without subjecting the sheets to the direct impact of a heating-flame.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a longitudinal sectional elevation of an annealing-furnace constructed in accordance with the invention. Fig. 2 is a transverse sectional elevation of the same on the line 2 2 45 of Fig. 1. Fig. 3 is a sectional perspective view of a portion of the receiving end of the furnace.

Similar numerals of reference are employed to indicate corresponding parts throughout the several figures of the drawings.

In the manufacture of tin and terne plates and other light sheet metal it is necessary to anneal the plates after the rolling operation—that is to say, to place the sheets in a furnace that has been previously heated to a temperature above the temperature at which the

sheets are rolled, and to retain said sheets within the furnace until the necessary softness is acquired. In the ordinary processes the stationary annealing-ovens are used, these being necessarily disposed at some distance from the rollers, and the sheets are usually stacked until a sufficient quantity has been rolled to fully charge an oven. The sheets become chilled and after losing heat it becomes necessary to employ a large quantity of fuel to reheat them to the desired temperature.

In carrying out the present invention the sheets are taken from the rolls A directly to the oven and no chilling of the plates or sheets may occur, so that a considerable saving of fuel is effected.

The portable furnace includes a structural-iron frame 1, provided with suitable bearings 2 for the reception of transverse shafts or axles 3, on which are mounted supporting-wheels 4, these wheels preferably traveling on rails 5, that extend from the rollers to a stationary annealing-furnace. The outer casing or jacket 6 of the furnace surrounds an inner muffle 7, and between the two is formed a continuous space in which is arranged a series of pipes 8, said pipes being provided with numerous perforations, through which jets of gas are directed against the inner wall 7, the number of pipes and the size of the jet-openings being sufficient to insure the heating of the oven or muffle to the desired temperature. That end of the muffle adjacent to the rolls A is open, as illustrated in Fig. 3, to permit the entrance and discharge of the sheets, and the outer wall or casing is preferably provided with openings for the entrance of the air necessary to support combustion.

The furnace is rolled to a point close to the rolls A and receives the sheets as they issue from said rolls, and after a sufficient quantity of sheets have accumulated the furnace may be removed to a stationary heating-oven and retained therein until the annealing operation is completed, or the portable furnace may serve merely as a conveyer to carry the sheets from the rolls to a stationary oven, and in many cases the oven may serve as a reheater in order to receive the sheets between roll-passes.

Having thus described the invention, what is claimed is—

1. A portable annealing oven or furnace, comprising a wheeled frame, an outer jacket carried thereby, an inner oven spaced from

the top, bottom and sides of the jacket, and forming a continuous combustion-space, the oven being opened at one end for the reception of the articles to be annealed, and a plurality of perforated gas-pipes disposed in said combustion-space, said pipes encircling the oven and being arranged to direct heating-jets against the entire outer surface thereof.

2. A portable annealing oven or furnace comprising a wheeled frame, an outer jacket carried thereby, an inner oven, the top, bottom and side walls of which are separated from the jacket by a continuous combustion-space, the oven being opened at one end for

the reception of articles to be annealed, and the corresponding end of the combustion-space being closed, and a plurality of perforated gas-pipes extending continuously around said inner oven and arranged to direct heating-jets against the entire outer surface thereof. 15 20

In testimony that I claim the foregoing as my own I have hereto affixed my signature in the presence of two witnesses.

AMBROSE RIDD.
